UNITED STATES PATENT OFFICE.

MILTON I. D. EINSTEIN, OF NEW YORK, N. Y.

EMBROIDERED ORNAMENTAL DOT.

1,409,214.

Specification of Letters Patent. Patented Mar. 14, 1922.

Application filed April 9, 1921. Serial No. 460,104.

To all whom it may concern:

Be it known that I, MILTON I. D. EINSTEIN, a citizen of the United States, residing at borough of Manhattan, city, county, and State of New York, have invented certain new and useful Improvements in Embroidered Ornamental Dots, of which the following is a specification.

This invention relates to a method of embroidering plush or fluffy dots or tufts for the ornamentation of textile fabrics such as veils, dress-goods or the like, and to the product resulting from carrying out said method.

15 The principal object of the invention is to provide an embroidered fluffy dot or tuft comprising a multiplicity of threads, of chenille or other suitable embroidery thread, of substantially equal length, each thread firmly secured at one end to a backing of textile fabric and having its other end free, all the threads being firmly sewed to the reverse side of the backing at or near the periphery of the dot and passing through 25 a restricted area of the backing near the center of the dot to emerge on the right side of the backing.

30 A further object of the invention is to provide a simple, quick and economical method of making such dots. Other objects will be apparent hereinafter.

35 For the sake of simplicity, the dots will be shown and described as circular in shape, but it is apparent that they may be made in any desired shape.

40 The invention will be best understood by reference to the accompanying drawings, illustrating a preferred embodiment thereof, and in which:

Fig. 1 is a diagrammatic drawing showing the initial steps of the method;

45 Figs. 2, 3 and 4 are views similar to Fig. 1 showing successive stages in carrying out the method of the invention;

Fig. 5 is a side elevation of a completely 50 sewn dot in which some of the stitches have been cut and fluffed; and

Fig. 6 is a perspective view of a completed dot made by the new method of the present invention.

In these drawings 1 represents a fragment 55 of a sheet of material, such as dress-goods, net, veiling, or the like, constituting a backing which is to be ornamented by embroidering thereon one or more of the fluffy dots made in accordance with the new method.

The embroidering may be done by hand or by the usual machine, and the backing is most desirably stretched on the usual embroidery-frame. The first step consists of 60 stitching in the circle 2, to be used as a guide in the further steps. The outline 3 of the completed dot is next stitched in, in the present instance in the shape of a circle, after which a few radial stitches 4, 65 extending from the outline 3 to the center thereof, are stitched in, all as shown in Fig. 1. These stitches form a spider which guides the operator in the subsequent steps and serves to strengthen the backing, which 70 in many cases is of sheer material such as silk crepe, and to prevent distortion of the same during the subsequent embroidering.

The space between the outline 3 and the guiding circle 2 constituting a border is then 75 filled in by a number of stitches 5, spaced very close together so as to practically entirely conceal the annular portion of the backing covered by these stitches 5. The stitches are preferably much closer together than shown in Fig. 2, which is merely to illustrate the extent of each individual stitch 5 rather than the number of such stitches. The backing is then successively covered with a series of radial stitches 6 80 overlying the stitches 5 and extending from the periphery 3 slightly nearer to the center of the guiding circle 2 than did the stitches 5. Upon the completion of the series of stitches 6, further series of stitches, 85 as 7, are applied to the backing, each successive series beginning at the periphery 3 and extending nearer the center of the figure than the preceding series of stitches until the desired thickness of embroidering has been 90 secured, at which time the last series of radial stitches 9 will extend from the periphery 3 to the very center of the guiding circle 2, as shown in Fig. 4.

When the radial stitches 9 have been applied, the outer edge of the figure is firmly stitched down by overcasting therearound a number of times to form a binding 8 which evens up the slightly uneven radial stitches and permanently secures said stitches to the 100 backing at the periphery. When the work has progressed to this stage, it will appear as shown at the left hand of Fig. 5.

The sewing is now completed and the radial stitches are all severed from the securing 110 bindings 8 on the right side of the material and fluffed up to form the completed

dot or tuft 10 as shown at the right of Fig. 5 and in Fig. 6.

It will be noted that all the radial stitches are still firmly anchored on the reverse side 5 of the backing to the peripheral binding 8 while their free ends extend through the restricted central area of the backing defined by the guide-circle 2 and are of substantially uniform length, thus producing a dot 10 symmetrical about its center.

The method of making dots may be practiced with extreme rapidity, and obviously is susceptible of various minor changes without departing from the spirit of the invention. For example the guide circles 2 and 15 outline 3 might be printed on the backing instead of stitched thereon, or they may be both printed and stitched.

What is claimed is:

20 1. An article of embroidery comprising a backing having a front side and a reverse side, a peripheral outline thereon, and a tuft of threads extending on one of said sides of the backing symmetrically in all 25 directions about a central point of said outline, each of said threads having a free end.

2. An article of embroidery comprising a tuft composed of embroidery threads, each 30 thread being secured to the reverse side of a backing at the periphery of the tuft, and all the threads of the tuft passing from said reverse side through a restricted central portion of the backing and emerging on the 35 right side of the backing as free ends, all the free ends being of approximately equal length.

3. The method of embroidering fluffy dots which comprises stitching a closed border on a backing, each stitch of the border extending 40 from the periphery towards the center and the stitches being of substantially uniform length, next overlaying said border with successive layers of similar radial 45 stitches, the stitches of each layer being of

uniform length, and extending slightly 45 nearer the center of the border than those of the last preceding layer, the stitches of the last layer all passing through the backing at a point near the center of the border, next binding the periphery of the border to the 50 backing, then cutting all the radial stitches on the right side of the backing at the binding to form free ends, and then fluffing the free ends.

4. The method of embroidering fluffy-dots 55 which comprises stitching a closed outline of the finished dot on a backing, next covering a border within said outline with a series of substantially radial stitches close together and of uniform length, next overlaying said 60 series of stitches with a number of successive series of substantially radial stitches extending from said outline toward the center of the figure, all the stitches of a series being of uniform length and the stitches of 65 each successive series extending nearer the center than those of the previous series, next binding all of said radial stitches to the backing at said outline, and then cutting all 70 of said radial stitches at said outline on the right side of said backing and fluffing said 75 stitches.

5. The method of forming an embroidered dot on a backing of textile fabric which 80 comprises stitching a closed border of closely 75 laid radial stitches having their outer ends at the periphery of the border and their inner ends short of the center thereof, then superimposing on said radial stitches a plurality of series of like stitches with the inner 85 end of each successive series of stitches approaching closer to the center of said periphery, then binding the outer ends of all radial 85 stitches at said periphery, then cutting said stitches at their outer ends and puffing up the loose ends so formed.

MILTON I. D. EINSTEIN.
